BUFFET OR THE LIKE

Ernest Herrmann, Hillsdale, N. J., assignor to Heywood-Wakefield Company, Gardner, Mass., a corporation of Massachusetts

Application March 14, 1955, Serial No. 35,037

Term of patent 7 years

(Cl. D33—13)

Fig. 1 is a front perspective view of a buffet embodying my new design;

Fig. 2 is a top plan view thereof, partially in cross section along the line 2—2 of Fig. 1.

Fig. 3 is a side elevation of the buffet.

Fig. 4 is an enlarged fragmentary cross section along the line 4—4 of Fig. 1; and

Fig. 5 is an enlarged perspective view illustrating one of the drawer pulls in detail, the concave front thereof being stippled to indicate contrast.

I claim:

The ornamental design for a buffet or the like, substantially as shown and described.
